UNITED STATES PATENT OFFICE.

CORNELUS KERKHOF, OF HACKENSACK, NEW JERSEY.

RECEPTACLE.

Application filed November 3, 1922. Serial No. 598,830.

To all whom it may concern:

Be it known that I, CORNELUS KERKHOF, a citizen of the United States, residing at Hackensack, in the county of Bergen and 5 State of New Jersey, have invented new and useful Improvements in Receptacles, of which the following is a specification.

This invention relates to the class of receptacles and more particularly to bottles 10 made of paper or the like.

An object of the invention is to provide a sanitary destructible receptacle of this character which, for all intents and purposes will possess the practical qualities of 15 a glass bottle of the kind usually employed as a container for milk.

A still further object of the invention is to improve the form and construction of containers of this type which will be inexpensive of production, highly efficient for 20 the purpose intended; one which will be strong and durable and not apt to be destroyed in transit or handling; one which will possess an appreciable measure of 25 rigidity, and one which when once used may be destroyed so as to avoid the risk of transmitting infectious diseases.

Another object of the invention is to provide a bottle of this character which is particularly constructed at its neck portion so 30 as to serve as a rigid seat for the customary closure cap.

With these and other objects in view, the invention resides in certain novel construction and combination and arrangements of parts, the essential features of which are hereinafter fully described, are particularly pointed out in the appended claims, and are illustrated in the accompanying drawings, in which:—

Figure 1 is a side view of the bottle partly completed, parts being shown in section.

Figure 2 is a sectional view of a portion of a bottle with the cap applied.

Figure 3 is a plan view of the clamping ring.

Figure 4 is a view similar to Figure 2 showing the clamping ring applied.

Figure 5 is a view similar to Figure 1 50 showing a slightly modified form of the invention.

Figure 6 is a similar view showing the second step incident to assembling the parts of the bottle.

Figure 7 is a similar view showing the

third step of assembling the parts of the bottle.

Figure 8 is a similar view showing the final step of assembling the parts of the bottle.

Figure 9 is a plan view of the clamping ring.

Figure 10 is a view similar to Figure 1 of the further modified form of the invention with the parts occupying their initial 65 position.

Figure 11 is a similar view showing the second step of assembling the parts.

Figure 12 is a similar view showing the final step of assembling the parts.

As stated, it is an important object of the present invention to provide a paper or destructible bottle which will be practical and highly efficient as a substitute for the well-known form of glass bottle. In order to accomplish this purpose of the invention, I have solely combined certain features of construction which will give to the bottle a high measure of strength and rigidity together with a novel form of reinforcement at the neck of the bottle so as to permit of the customary application thereto or removal therefrom of the usual form of cardboard sealing disk.

In carrying the invention into practice and with particular reference to the form of my invention shown in Figures 1 to 4 inclusive the bottle consists of a substantially frusto-conical body 10 formed of paper or the equivalent thereof of suitable texture. Embracing the restricted end of the body 10 is a mouth piece 11 constructed of metal or suitable stiff material such as fiber. This mouth piece is provided with an annular external collar 12, an angular wall 13 and a flared annular wall 14, the free edge of the latter being rolled at 15 as shown.

On reference to Figure 1 which illustrates the first step in assembling the several parts of my improved bottle, it will be observed that the restricted walls of the body 10 are normally extended at 16 to a point slightly above the angular shoulder 13. I then upset the extension 16 against the shoulder 13 as shown in Figure 2. In order that this upset portion may be securely clamped against the shoulder 13 I employ a resilient split clamping ring 17 adapted to be forced into the mouth piece to be contracted by the flare of the wall 14 as the ring ap-

proaches the shoulder 13. The ring is finally firmly seated against the upset extension 16 as shown in Figure 4. When the parts are assembled as shown in Figure 4, 5 the neck of the bottle presents a highly satisfactory combination which gives to the neck a high measure of rigidity so that the closure cap 18 shown in Figure 4 can be readily applied to or removed from the 10 bottle without disorganizing the neck portion of the bottle or causing collapse thereof. This feature is very desirable when used in connection with a body 10 which is frusto-conical as described. I find a frusto- 15 conical bottle is capable of standing great strains without possibility of accidental collapse.

In the form shown in Figures 5 and 9 inclusive the arrangement of parts is somewhat a reversal of that referred to in the 20 first embodiment of the invention. The mouth piece 19 consists of a rigid or stiff annular wall 20, a horizontal shoulder 21 adapted to serve as a seat for the closure 25 cap, and an angular downwardly flared wall 22 which is curved into the annular wall 20 as shown at 23.

Upon reference to Figure 5 it will be observed that the split ring 24 is arranged up- 30 on the exterior of the restricted portion 16 of the body 10 and that said extension 16 rises to a slight extent above said ring 24. The annular wall 20 of the mouth piece is 35 interiorly positioned with respect to the extension 16. After the parts have been initially brought together as shown in Figure 5 the mouth piece is moved in a downward direction toward the ring 24. This deflects the extension 16 of the bottle and causes it 40 to conform to the shape of the underside of the curve 23 of the mouth piece. In so doing the neck of the body portion 10 is firmly sandwiched between the wall 20 and the aforesaid clamping ring 24.

45 When this second step of assembling the parts has been accomplished as shown in Figure 6, the wall 22 is bent downwardly at 25 as shown in Figure 7 and then inwardly at 26 as shown in Figure 8. This completes 50 the formation of the neck of the bottle so as to give to the neck a maximum measure of efficiency and rigidity. On reference to the form shown in Figures 10 to 12 inclusive, I employ a cylindrical body 27, a mouth piece 28 and a resilient ring 29. The mouth piece is provided with an annular wall 30, a curved wall 31 and a closure seat 32. The upper wall of the body 27 is embraced by the terminal of the wall 31. The 55 parts are brought together so that the upper walls of the body 27 are curved inwardly at 32 as shown in Figure 11 to conform with the curvature of the wall 31. The resilient ring 29 is normally on the interior of the 60 body 27. In assembling the parts the ring 65

29 is brought up so as to underlie the curved portion 32 and the terminal of the wall 31 is then pressed in at 33 as shown in Figure 12. This brings the curved portion 32 and the wall 31 in concentric relation 70 with respect to the cross-sectional form of the ring 29. The parts are now firmly clamped to each other with the wall 32 sandwiched between the ring 29 and said wall 31.

In either of the forms of my invention 75 herein shown and described, the essentials of construction consist of a rigid mouth piece, a resilient or otherwise suitably constructed clamping ring and the flexible wall at the neck of the body of the bottle, all of which 80 parts are brought together so as to simplify the construction of containers of this class and give to same a maximum measure of strength and durability.

While I have described what I deem to be 85 the most desirable embodiment of my invention, it is obvious that many of the details of construction may be varied without in any way departing from the spirit of my invention, and I therefore do not limit myself 90 to the exact details of construction herein set forth nor to anything less than the whole of my invention limited only by the appended claims.

What is claimed as new is:—

1. A receptacle including a paper body, a 95 resilient clamping ring adapted to be placed over the neck of the body, a mouth piece of relatively rigid material passed into the neck of the body, and a downwardly flared wall formed on said mouth piece serving to deform the walls of the neck to bring the same in clamping confinement between said ring and mouth piece.

2. A receptacle including a paper body, 105 a resilient clamping ring adapted to be placed over the neck of the body, a mouth piece of relatively rigid material passed into the neck of the body, and a downwardly flared wall formed on said mouth piece 110 serving to deform the walls of the neck to bring the same in clamping confinement between said ring and mouth piece, said mouth piece provided with a shoulder serving as a seat for a disk closure.

3. A receptacle including a paper body, a resilient clamping ring passed over the neck of said body, a mouth piece of relatively rigid material having a downwardly flared wall and an inner horizontal flange serving 120 as a valve seat for a closure disk, said mouth piece insertable in the neck of the body to cause said flared wall to co-act with the periphery of said neck to cause the same to be brought into clamping confinement between the said clamping ring and said mouth piece.

In testimony whereof I have affixed my signature.
